BOTTOM FILLER

Isidor Tarlow, Brockton, Mass.

Application March 20, 1935, Serial No. 11,994

3 Claims. (Cl. 36—30)

This invention relates to fillers for the forepart cavity of shoes and to the process of its manufacture. The bottom-filler of this invention which functions to level the bottom of the shoe after lasting and to prepare the unbottomed shoe for outsoling, may be used to fill the forepart cavity of any type of shoe where the process of manufacture produces such a cavity, but is especially useful in welted shoes.

10 The object of this invention is to produce a bottom-filler in one piece, preferably from sheet material of a substance having the qualities of preventing the formation of gutters in the insoles of a shoe after wear; of being incapable of shifting within the cavity to lump and create depressions and thus to maintain a flat insole during wear of the shoe; and of inability to crawl out of place. Further characteristics of the preferred form of the bottom-filler permit air circulation or "breathing" and promote flexibility 20 in the shoe.

To the accomplishment of these objects and such others as may hereinafter appear, as will readily be understood by those skilled in the art, the invention comprises the features and combinations of parts and processes of manufacture hereinafter described and then particularly pointed out in the appended claims.

The nature and scope of the invention and its manufacture will be understood from a description of the preferred embodiment thereof illustrated in the accompanying drawing, in which:

Figure 1 is a view, in perspective, of a portion of a sheet of material usually supplied in strip form from which the filler may be processed;

Fig. 2 is a view, in plan, of a fragment of a strip of the filler material showing how half-sole shaped pieces may be dinked therefrom;

Fig. 3 is an edge view of a one-piece bottom filler showing its skived shank end; and

Fig. 4 is a view, in plan, of the preferred form of the bottom-filler produced by the process.

In the embodiment of the invention illustrated in the drawing 10 represents a sheet or piece of rubber stock known as friction-scrap. Ordinarily, as obtained in the form of waste, friction-scrap retains a considerable degree of elasticity and is highly flexible. The friction-scrap useful for bottom-fillers may be the waste from worn tires, both cord and fabric, and may also include the like waste from hose and belting or any similar waste having a contained reinforcement of cotton fibre or its equivalent. These sheets or strips of friction-scrap vary in thickness. The bottom-filler, which is used to level the bottom of a

shoe before outsoling, requires a thickness or weight that will fill the cavity between the insole and outsole formed by the overlasted margin of the upper or, in a welt shoe, the projecting sewing-rib to which the overlasted upper has been secured by the inseam. The forepart cavity to be filled is thus bounded, except at its shank end, by the overlasted upper.

If the sheet or strip 10 is too thick, a sheet or strip 20 of the desired thickness is obtained by splitting as indicated in Fig. 1. Fig. 2 illustrates the dinking of a plurality of half-sole shaped pieces 25 from a strip 20, although it will be understood that these pieces 25 may be cut from the friction-scrap as first received if of proper thickness for the forepart cavity of the particular shoes being manufactured. In practice some splitting or skiving to final thickness is ordinarily required.

Each half-sole shaped piece 25 is then skived 20 to a relatively wide bevel edge 32 at its straight or shank end 35 (see Figs. 3 and 4) so that this end of the filler may merge with the insole at the shank of the shoe and thus completely effect its leveling. The bottom-filler 30 as thus produced, 25 may be used in the shoe but it is preferred that another step be performed in its manufacture.

Because friction-scrap is principally rubber provision should be made for a circulation of air therethrough in order to overcome an overheating of the feet of the wearer of the shoes. This is called "breathing". Accordingly at a convenient stage of the process, most efficiently before the half-sole shaped pieces 25 are dinked, the bottom-filler is made foraminous as by perforating 30 with a multiplicity of small holes 38. These holes are not so large as to permit forming depressions in the filler when it is distorted from any cause as by the varying weight of the wearer of the shoe upon the overlying insole or in flexing with the 35 forepart of the shoe. In practice holes $\frac{1}{8}$ to $\frac{1}{4}$ of an inch in diameter have been found efficient for breathing and for ensuring a permanent flat sock face on the insole of the shoe. The bottom-filler 40, Fig. 5, is provided with both shank end 40 bevel 32 and "breathing" perforations 38. It will be understood that the heavy dot or dash lines on the figures of the drawing indicate the layers of continuous strands of cotton fibre character- 45

istic of worn tire friction-scrap. The bottom-filler of this invention will not crack in flexing, is sufficiently elastic to be comfortable but not sufficiently so to lose the parallelism of its faces so that the outsole wears even. The new filler, with its quality of non-distortion, 50

55

prevents the formation of gutters in the sock face of the insole following the line of channelling, it cannot shift, crawl or lump to create uncomfortable depressions because in one piece 5 within the forepart cavity and yet imparts flexibility in all directions of flexure in the shoe. The new filler, when embodied in welt shoes, engages and supports the insole sewing-rib to protect the inseam from undue strains. Those skilled in the 10 art of shoe-making will understand that the new filler will be secured within the forepart cavity by a suitable rubber or latex cement.

The nature and scope of the invention having been indicated, and its embodiment and process 15 of its manufacture having been specifically described, what is claimed as new, is:—

1. A one-piece shoe bottom filler prepared off the shoe to final size for insertion within a shoe

bottom cavity consisting of a sheet principally of rubber stiffened by a fibre reinforcement comprising continuous strands of the fibre situated in layers throughout the thickness of the sheet.

2. A one-piece shoe bottom filler according to 5 claim 1, characterized by a multiplicity of perforations of such size as to avoid peripheral depression by excess pressure localized to the area about one or more perforations.

3. A one-piece shoe bottom filler prepared off the 10 shoe to size for filling the shoe bottom cavity within the sewing rib of a welt shoe consisting of a sheet principally of rubber reinforced with strands of fibre extending entirely across the filler and through the edge walls thereof to stiffen said 15 edge walls for supporting the surrounding sewing-rib.
